CLAIM

The ornamental design for a waste container, as shown and described.

DESCRIPTION

FIG. 1 is a perspective front view of a waste container showing the new design;

FIG. 2 is a front view thereof;

FIG. 3 is a top view thereof;

FIG. 4 is a first side view thereof;

FIG. 5 is a second side view thereof;

FIG. 6 is a back view thereof; and,

FIG. 7 is bottom view thereof.

The broken lines in the figures are included for the purpose of illustrating portions of the waste container that form no part of the claimed design.
